UNITED STATES PATENT OFFICE.

HAROLD W. SHONNARD, OF MONTCLAIR, NEW JERSEY, ASSIGNOR TO ELEVATOR SUPPLIES COMPANY, INC., A CORPORATION OF NEW JERSEY.

COLLAPSIBLE GATE.

Application filed April 17, 1926. Serial No. 102,605.

Folding or collapsible gates such as are commonly used on elevator cars, and in other localities where economy of space is desirable, are made of pairs of parallel metal bars united by a web composed of flat metal strips crossing each other and pivotally connected among themselves. Some of the crossed slats of the webbing are connected with certain of the parallel bars by fixed pivots; and thus the webbing expands or contracts on the "lazy tongs" principle as the parallel bars are separated or pushed together in closing or opening the gate.

In gates of this kind, the mutual connections among the slats that form the webbing are formed by simply passing rivets through openings that register where two slats cross, and forming heads in the usual manner on each rivet to hold it in place. This mode of fastening is the cause of trouble and annoyance.

In the course of use the rivet holes wear larger and larger so that the slats and rivets rattle noisily when the gate is pushed back and forth. To prevent this so long as possible, the rivets are made extra tight, and, in consequence, when the gate is new it is stiff jointed and harder to operate.

Again, many of these gates are arranged in combination with mechanical contrivances for opening and closing them. In order to work properly, such contrivances must be adjusted in proportion to the effort to be exerted with each operation. Since gates made as above described move more and more easily as they wear loose, these mechanical gate operators must be constantly readjusted to fit new conditions. This entails a considerable expense in the employment of skilled men.

Another imperfection found in gates of this kind is in the fact that the web is imperfectly confined between the pairs of parallel bars, except where pivoted to them at fixed points. This is a cause of rattling and of undue wear.

My present invention provides a structure for folding gates of this general type in which there is used a novel form of pivotal connection between the slats that constitute the web as well as between these slats and the pairs of parallel bars, whereby wear is almost entirely eliminated. This makes it possible to make a new gate which will move

with the utmost ease without looseness or rattling, and with the assurance that the force necessary to move the gate shall remain substantially constant in the course of use. This eliminates the necessity of constantly altering the adjustment of mechanical operators.

It is another novel and advantageous feature of my present invention that it provides a secure non-rattling supporting and steady contact between the web and the intersecting pairs of parallel bars. This feature of my improvement applies not only to the fixed pivotal connections but also to the pivots that travel up and down these bars as the web expands and contracts in closing and opening the gate.

The invention is illustrated in a preferred form in the accompanying drawings wherein Figure 1 is a diagrammatic view in elevation of a complete folding gate, Figure 2 is a view in elevation on a larger scale of a portion of the collapsible web and Figures 3, 4 and 5 are sectional views of three different forms of pivotal connections used in my improved gate.

The parallel bars (usually vertical) are shown in Figure 1 at 10, and, as shown in Figures 3 to 5, these are preferably made of pairs of angle bars 10 and 11 which are held together by the fixed pivotal joint shown in Figure 4.

The crossed slats constituting the lazy tongs web that unites the bars 10 are shown at 12 and 13 in Figures 3, 4, and 5.

The intersections at which these slats are pivotally, and yet freely united, are constructed as shown in Figure 3. Figure 4 shows certain special points of intersection at which the web is united to the parallel bars. Figure 5 shows the construction at the extremities of slats 12 at the two sides of the gate where there is no intersection of the slats. This last may be termed a single roller joint, the other two being double joints.

As shown in Figures 3 and 4, the slots are suitably perforated at their intersection and the periphery of each opening is spun slightly outward as at 14. This affords an annular shoulder 15 into which is tightly fitted the flange of a steel bushing 16 which passes through the aperture and is headed down on the outside as at 17. The flanges

of the bushings lie preferably in contact between the web slats 12 and 13 as shown in Figures 3 and 5.

Through the registering openings of the contiguous bushings 16 at each intersection there passes a hard bronze pivot pin 18. This has reduced ends, as shown, upon which are mounted the steel discs 19, preferably held in place by upsetting the ends of the pin 18, as at 20.

The discs 19 may either be hard and fast on the ends of the pin 18, or they may be loose enough to revolve and thus constitute rollers.

In either case they occupy the space between the wings of the channel bars 10, 11, as shown, being slightly less in diameter than the space between these wings. The amount of play either parallel to or at right angles to the plane of the web is quite small, and in consequence there will be no appreciable rattling, while all parts of the web will be confined to a single plane by the pairs of parallel bars.

Where it becomes necessary to actually unite the bars 10, 11 to the web by fixed pivots, the structure is preferably as shown in Figure 4.

Here each hard bronze pin 18^a has reduced ends making a fairly snug revolving fit with registering openings in the bars 10, 11. The ends of 18^a are upset as shown, in a manner to bring the outer surfaces of the discs 19 against or very near to the inner surfaces of the bottom of the channel of each bar. The pivot pin 18^a thus unites the pairs of parallel bars 11, 10 to each other while also affording spacing means to keep these bars 10 and 11 the right distance apart.

At the single uncrossed extremities of certain slats 12 on the two sides of the gate, the structure is the same as that shown in Figure 3, save that the slat 13 and collared bushing 16 are replaced by the cylindrical spacing collar 21 which fits snugly upon the pin 18 and abuts at its ends upon the bushing 16 and the disc 19 respectively.

It will be seen that my invention greatly reduces wear at pivotal points and makes it possible to regulate the fit of the pivots at the intersections of the web slots so that they shall not be too tight and stiff at first and shall give substantially the same resistance to movement after use as at first. The structure shown also provides means for noiselessly guiding and confining the web slats as well as properly securing and spacing the pairs of parallel bars.

What I claim is:

1. In a folding gate of the type described, intersecting web slats having registering openings provided with steel bushings, and brass pivot pins fitting said bushings.
2. Apparatus as in claim 1 wherein each pivot pin has reduced ends and wherein steel discs are mounted on said reduced ends.
3. Apparatus as in claim 1 wherein the peripheries of the registering openings are bent outward to form interior shoulders and wherein the bushings are made to fit said shoulders and are provided with interior and exterior flanges adapted to secure the bushing in place.
4. Apparatus as in claim 1 wherein the bushings occupying registering openings have flat interior flanges in contact the one with the other.
5. In a folding gate, intersecting web slats having registering openings the periphery of said openings being bent outward to form interior shoulders and having bushings made to fit said shoulders and provided with flanges adapted to secure the bushings in place.
6. In a folding gate intersecting web slats having registering openings the periphery of said openings being bent outward to form interior shoulders, bushings fitting said shoulders and means for holding said bushings in place.

In testimony whereof I have hereto affixed my signature.

HAROLD W. SHONNARD.
